UNITED STATES PATENT OFFICE.

ROY HUSTON, OF SEATTLE, WASHINGTON.

FENCE-WIRE SPACER AND HOLDER.

Application filed June 11, 1926. Serial No. 115,409.

This invention relates to wire spacing devices especially designed to aid in properly spacing and positioning fence wires when securing the same to posts, an object being to provide a device for this purpose which may rest upon the ground to raise and hold the wires in place, or held against raising to depress and space the wires in such manner as to hold them in proper spaced relation while they are being attached, and leave the hands of the workman free to attach the wires.

With the above and other objects in view, the invention further includes the following novel features and details of construction, to be hereinafter more fully described, illustrated in the accompanying drawings and pointed out in the appended claim.

In the drawings:—

Figure 1 is an elevation showing a portion of a fence and illustrating the use of the invention.

Figure 2 is an enlarged fragmentary elevation showing a portion of the spacer rod and one of the spacing elements.

Figure 3 is a fragmentary perspective view of the lower end of the rod and the base member.

Referring to the drawings in detail wherein like characters of reference denote corresponding parts, the reference character 10 indicates a rod preferably of metal which has secured to its lower end a base member in the form of a stirrup 11. The upper end of this stirrup carries a sleeve 12 which receives the lower end of the rod 10 and is secured to the sleeve by means of a set screw 13. If desired, the rod 10 may be provided with a socket (not shown) to receive the inner end of a set screw so as to more securely hold the stirrup upon the rod. If desired, the stirrup may be otherwise permanently attached to the rod.

Spaced along the rod 10 is a plurality of wire engaging elements 14 each of which comprises a body having an opening 15 therein for the passage of the rod 10. An offset hook 16 extends from one end of the body and is designed to receive a wire strand as indicated at 17 in Figure 2 of the drawings. The hook 16 extends outward from the top at one side edge of the body and the adjacent side edge of said body inclines downwardly and inwardly as shown in Figure 2 of the

drawings. By means of the arrangement and disposition of the hook 16, a seat 18 is provided at one end of the body 14 between the hook and the rod 10 so as to receive a wire strand as indicated at 19 in Figure 2 of the drawings.

The wire engaging elements 14 are adjustably positioned along the rod 10 and are held in adjusted position by means of set screws 20.

When attaching the wires A to the posts B, if there is a depression in the surface of the ground, the hooks 16 are engaged with the wires as indicated at 17 in Figure 2. One foot of the workman may then be positioned within the stirrup 11 and the wires depressed and held in depressed position while being attached to the post. This arrangement is illustrated in Figure 1 of the drawings. Should it be necessary to raise the wires to properly position them, the wires are engaged with the wire engaging elements 14 as shown at 19 in Figure 2. The stirrup 11 will then provide a base which may rest upon the ground while the wires are being properly attached.

The invention is susceptible of various changes in its form, proportions and minor details of construction and the right is herein reserved to make such changes as properly fall within the scope of the appended claim.

Having described the invention what is claimed is:—

A fence wire spacing device comprising a rod, wire engaging elements adjustably spaced along the rod, each of said elements comprising a body having a rod receiving opening extending longitudinally therethrough, an offset hook extending from the top of the body at one side edge of the latter and spaced from the rod receiving opening and defining a wire receiving seat at the top of the body between the hook and the rod, and the bill of the hook extending downward and defining a second wire receiving seat within the hook, a downwardly and inwardly inclined side edge extending along the body from the second wire receiving seat, and a foot engaging member at the lower end of the rod.

In testimony whereof I affix my signature.

ROY HUSTON.
